METHODS OF WASHING TEXTILE FABRICS

Walter Kling and Hermann Lange, Dusseldorf, Germany, assignors to Bohme Fettchemie G.m.b.H., Dusseldorf, Germany, a corporation of Germany

No Drawing. Filed July 27, 1954, Ser. No. 446,146

Claims priority, application Germany July 29, 1953

10 Claims. (Cl. 252—152)

This invention relates to a method of laundering textile fabrics and to a composition of matter for laundering such fabrics more efficiently.

It is well known that heavily soiled fabrics of all types are difficult to launder to absolute cleanliness with ordinary washing agents such as laundry soaps and detergents, particularly if the soiling substance is of a fatty nature or contains dyes. Practical experience has also shown that this is also true of soiled synthetic fabrics such as nylon, Perlon, Orlon, Dacron and others, despite the fact that the opinion has often been expressed in the literature that such synthetic fibers are particularly easy to cleanse. Moreover, synthetic fabrics have a tendency to undergo a gray or brownish discoloration after only a few times of laundering with the washing agents now generally in use. This discoloration becomes more accentuated in varying degrees in places upon the fabric which are subjected to heavy wear and perspiration, such as, for example, the armpits, cuffs and the collars of shirts, blouses, jackets and the like.

It is an object of the present invention to provide a method of laundering soiled fabrics of all types which will completely remove the soiling substance from the fabric.

It is another object of this invention to provide a composition of matter for laundering fabrics which, when added to the washing solution, will aid in completely ridding soiled fabrics of all types of soil without any special manipulation of the fabric in the washing solution.

We have found that good laundering results can be obtained if both the fiber and the soil are charged with a positive electrical charge during the washing operation by adding a sufficient amount of a cation-active substance to the washing solution.

It is well known in the art that in ordinary laundering processes with the usual anion-active substances the fiber and the soil have a negative charge imparted thereto. It is generally believed in the art that the electrostatic repulsion created thereby between the fiber and the soil contributes considerably to the removal of the soil. It is further known that cation-active substances added to the washing solution in insufficient quantities have a negative cleansing effect; i.e., they effect an increased attraction between the fiber and the soiling substance.

We have surprisingly discovered that in laundering fabrics composed entirely of synthetic fibers, such as, for example, polyester fibers, polyamide fibers, polyisocyanate fibers, fibers made from vinylpolymerisates such as polyvinylchloride, polyvinylacetate and the like, fibers made from polymerisates of acrylic acid derivatives such as

2

acrylic acid esters, acrylic acid nitriles and the like, it is possible to remove all types of soil and obtain a perfectly clean fabric if the washing solution contains a sufficient amount, per unit volume of solution, of at least one cation-active substance to impart a positive charge to the soil and the fabric.

Cation-active compounds which, when present in sufficient concentration, are suitable for use in connection with our invention are cation-active onium compounds, such as, for example, ammonium, sulfonium, phosphonium and like compounds. While, in general, any cation-active onium compound is a suitable additive for the purpose of charging the fiber and soil with a positive charge, those onium compounds comprising at least one high-molecular hydrocarbon radical with at least 6 and no more than 20 carbon atoms in its molecule are preferred. The hydrocarbon radical may also contain heteroatoms, heteroatom groups or substituents.

Specific examples of suitable onium compounds are the following, which are derived from ammonia or organic nitrogen compounds:

Trimethyl-hexyl-ammonium chloride
Trimethyl-dodecylammonium chloride
Trimethyl-octadecylammonium methosulfate
25 Dimethyl-dodecyl-benzyl-ammonium chloride
Hexylpyridinium-bisulfate
Octadecylpyridinium chloride
Hexylquinolinium chloride

30 Other examples of suitable onium compounds are the following in which one or more of the alkyl radicals contain heteroatoms or heteroatom groups:

Octadecyo-carbomethyl-trimethyl-ammonium chloride
Dodecoxy-carbomethyl-pyridinium-methosulfate

35 Naphthoxy-carbomethyl-quinolinium chloride
Abietyloxy-carbomethyl-quinolinium bromide
Di(dodecoxy-carbomethyl)-dimethyl-ammonium methosulfate

40 Octadecyl-amino-carbomethyl-trimethyl-ammonium chloride

Octadecyl-anilino-carbomethyl-pyridinium-bisulfate

Dodecoxymethyl-trimethyl-ammonium chloride

Octadecylthiomethyl-triethyl-ammonium bisulfate

45 Octadecyl-carbaminomethyl-pyridinium chloride

Octadecyloxy-carbaminomethyl-pyridinium-methosulfate

and the like, as well as the corresponding compounds containing a quaternary phosphorus atom or arsenic atom, or a tertiary sulfur atom, such as, for example di-

50 methyl dioctyl phosphonium chloride, trimethyl dodecyl phosphonium sulfate, triethyl octadecyl phosphonium chloride and the like as well as the corresponding alkyl arsonium or alkyl stibonium salts respectively, dimethyl dodecyl sulfonium chloride, dimethyl octadecyl sulfonium methosulfate and the like.

If, for economic reasons, it is necessary to carry out our method of laundering with low concentrations of cation-active substances in the washing solution, the effect of placing a positive electrical charge upon the fiber and

60 the soil can be enhanced by the additional and simultaneous use of other types of cation-active compounds such as, for example, acid salts or acids, which adjust the pH of the washing solution to acid reaction, or of 65 easily absorbable multivalent cationic compounds such as, for example, salts of aluminum and the like.

Compounds suitable for use in accordance with our invention to augment the effect of low-concentration solutions of onium compounds by changing the pH of such solutions to acid reaction include inorganic and organic acids such as, for example, hydrochloric acid, sulfuric acid, phosphoric acid, boric acid, formic acid, acetic acid, lactic acid and adipic acid, as well as acid salts such as, for example, bisulfates, monophosphates, mononitrates and the like.

Multivalent cationic compounds which are suitable to augment the electrical charging effect of low-concentration solutions of onium compounds include inorganic and organic salts of aluminum, such as, for example, aluminum sulfate, aluminum lactate and aluminum formate, as well as salts of other polyvalent metals or also salts of polyvalent organic bases.

The amounts of additives which will produce the desired effect of charging the fiber and the soil with a positive electrical charge depend largely upon the type of fiber, upon the nature and reaction of the soil, upon the volume of washing solution and, last but by no means least, also upon the composition of the cationic additives, particularly the cationic washing agent.

The proper amount of cation-active additive can be most easily determined by the laundering results, but it may also be determined at any time during the laundering process by flocculation tests or by electro-kinetic test.

While we have thus far described a method of laundering synthetic fabrics, the general concept of our invention, namely to provide the fiber and the soil with a positive electrical charge during at least a portion of the washing operation, can be applied to textile fibers in general regardless of the type of fiber of which such fabrics are composed.

Thus, for example, if a batch of soiled laundry contains fabrics made of both synthetic and natural fibers, the washing solution is provided with cation-active agents such as the onium compounds described above and, if necessary, the above-described agents which augment the positive electrical charging effect of the cation-active agents on the fiber and the soil. In addition, this washing solution is provided with an additive comprising cationic colloids whereby the positive electrical charging effect is still further augmented.

Cationic colloids which are suitable for this purpose in accordance with our invention include high-molecular, oxygen-containing compounds such as polyalcohols, polyetheralcohols or polyethers and their derivatives. Examples of such colloids are alkylcelluloses, such as oxyethylcellulose, as well as corresponding starch derivatives, chitosamines, polyalkyleneoxides, such as polyalkyleneoxide waxes, and the like.

These cationic colloids are added to the washing solution in amounts ranging from 0.01 to 0.5 gm./liter, depending upon the composition of the washing solution and the operating conditions.

If the fabrics to be laundered are very heavily soiled, it is advantageous to employ a multiple-bath washing process wherein the individual washing solutions have approximately the same composition as in the above-described single-bath process.

We have found that improved laundering results are obtained if the heavily soiled fabrics are subjected to a multiple-bath washing process in which at least one solution charges the fiber and the soil negatively and at least one solution charges the fiber and the soil positively. In other words, the fabrics to be laundered are washed part of the time in an anion-active washing solution and part of the time in a cation-active washing solution.

The number and sequence of the anion-active and cation-active washing solutions can be varied between wide limits, depending upon the amount and nature of the soil and the types of fibers in the batch of laundry to be washed.

This multiple-bath washing method is applicable to all types of textile fabrics including cotton, artificial wool, linen, natural wool, rayon, natural silk, as well as all types of synthetic fibers. It is particularly well-adapted for washing fabrics made of synthetic fibers the cleansing of which has been found to present much greater difficulties than originally anticipated.

Anion-active washing agents suitable to be added to the washing solution to impart a negative electrical charge to the fiber and the soil in the multiple-bath method include all of the well-known washing agents, such as soaps, alkyl sulfates, alkyl sulfonates, alkyl aryl sulfonates, and the like.

Cation-active washing agents suitable to be added to the washing solution to impart a positive electrical charge to the fiber and the soil in our multiple-bath method include all of the onium compounds disclosed above in connection with the single-bath methods. As in the single-bath methods, the positive electrical charging effect upon fiber and soil may be augmented by the addition of organic and inorganic acids and acid salts, polyvalent metal salts and cationic colloids.

The washing solution employed in the washing process in accordance with our invention may at the same time contain any of the well-known non-ionic, surface-active compounds. They include, for example, alkyleneoxide addition products of higher molecular alcohols, amines, mercaptans, carboxylic acids, sulfonic acids or their amides, particularly the addition products of ethyleneoxide; also the esterification products of higher molecular carboxylic acids or the etherification products of higher molecular alcohols with polyethyleneoxide condensates, and the esterification products of higher molecular carboxylic acids or the etherification products of higher molecular alcohols with polyalcohols or polyetheralcohols, such as, for example, polyglycerines, pentaerythritol, sorbitol, sugars and the like. The use of such compounds in conjunction with the cation-active compounds disclosed above further improves the washing results obtained, particularly if the soil is of a fatty nature.

The following examples will enable persons skilled in the art to understand our invention more completely. However, it is understood that our invention is not limited to the conditions, quantities and specific compounds disclosed in these examples.

Example I

Ladies' brown stockings made of polyamide fibers (Perlon) were washed at 35° C. in an aqueous bath which contained 1.2 gm./liter tetradecyl-pyridinium-bromide. The weight ratio of washable goods to aqueous bath was 1:50, and the pH of the bath was about 7. The stockings were very satisfactorily cleansed.

Example II

Ladies' white undergarments made of polyamide fibers (nylon) were washed in the usual manner in an aqueous bath containing 0.3 gm./liter octadecoxy-carbomethyl-cyclohexyl-dimethylammonium chloride and 1 gm./liter acetic acid at 40° C. and at a pH of about 3, then rinsed, spin-dried and finally air-dried. The undergarments were clean and pure white.

Example III

Men's white shirts made of terephthalic acid ethylene-glycol polyester fibers (Dacron) were soaked for half an hour at 40° C. in an aqueous bath which contained 0.5 gm./liter hexadecoxy - carbomethyl - trimethyl - ammonium chloride, 0.5 gm./liter aluminum formate and 0.5 gm./liter formic acid. The pH of the bath was about 3. The shirts were then washed in this solution with moderate rubbing, and when necessary the highly soiled edges of the collar and the cuffs were treated with a concentrated solution of the cation-active washing agent. The shirts were finally rinsed and dried in the usual manner.

The soil was completely removed and the material did not turn gray.

Example IV

Men's colored socks made of polyacrylic nitrile fibers (Orlon) were vigorously washed in an aqueous bath which contained 0.4 gm./liter octadecyl-trimethyl-ammonium bisulfate, 0.2 gm./liter of a condensation product of 1 mol octylphenol and about 9 mols ethyleneoxide, and 0.5 gm./liter acetic acid, the bath being at a temperature of about 30° C. and its pH being about 4. Soil and perspiration, as well as soil and color stains originating from the shoes, which are common with synthetic fibers, were completely removed from the socks.

Example V

Ladies' white blouses made of polyamide fibers (nylon) were washed in an aqueous bath at 40-50° C. The bath contained 0.4 gm./liter octadecoxy-carbomethyl-trimethyl-ammonium chloride, 1 gm./liter acetic acid and 0.03 gm./liter methyl-cellulose. The blouses were absolutely clean when removed from the bath and they did not turn gray.

Example VI

Colored patterned sweaters made of wool were washed at 30° C. in an aqueous bath which contained 1.5 gm./liter tetradearylpyridinium bisulfate and 0.1 gm./liter chitoseamine (produced by alkaline degradation of chitin and subsequent neutralization with acetic acid). The sweaters were very clean, the colors were bright and the patterns were clear.

Example VII

Ladies' colored nightgowns made of polyamide fibers (Perlon) were washed at 25° C. in an aqueous solution which contained 0.3 gm./liter tetradeoxy-carbomethyl-trimethyl-ammonium chloride, 0.2 gm./liter of condensation products of 1 mol. dodecylalcohol and about 10 mols ethyleneoxide, 0.5 gm./liter acetic acid and 0.05 gm./liter oxyethylenecellulose. The nightgowns were absolutely clean, the weave showed up very clearly, the material was soft to the touch, and the colors were clear and bright.

Example VIII

Woolen goods, highly soiled with dust, soot and mineral oil, were washed for half an hour at 40° C. in a paddle-type washing machine with a washing solution containing 0.6 gm./liter octadeoxy - carbomethyl - cyclohexyl - dimethyl-ammonium chloride, 1 gm./liter acetic acid and 0.03 gm./liter methylcellulose. The washing solution was then drained off and the goods were rinsed. Subsequently, the goods were washed for about one hour at the same temperature in another bath containing 1 gm./liter sodium lauryl sulfate and 1 gm./liter sodium carbonate. The washed goods were clean, odorless and the fiber effects were clear.

Example IX

Men's white shirts made of polyamide fibers (nylon) which had been worn for a long time without washing were washed for 15 minutes at increasing temperatures from 20 to 60° C. in a drum-type washing machine, holding a washing solution containing 1.2 gm./liter sodium-dodecyl benzene sulfonate and 0.5 gm./liter sodium tri-polyphosphate. The solution was then drained off, the goods were rinsed, and subsequently subjected to a second washing run at 50° C. for 15 minutes in a solution containing 0.5 gm./liter hexadecyltrimethyl-ammonium chloride and 1 gm./liter acetic acid. The goods were found to be clean without spot-cleaning.

While we have given specific examples for practicing our invention, we wish it to be understood that various modifications and changes can be made in the method of practicing our invention, and the quantities and conditions

disclosed herein, without departing from the spirit of our invention and the scope of the following claims.

We claim:

1. The method of cleansing a soiled synthetic textile fabric, which comprises washing said fabric in a cation-active aqueous solution consisting essentially of water and from about 0.85 to about 1.5 gm./liter of a cation-active washing composition comprising (1) from about 23% to about 44% of an organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, (2) from about 33% to about 77% of a lower alkanoic acid and (3) from about 0% to about 33% of an additive stable in said cationic active aqueous solution selected from the group consisting of aluminum salts of lower alkanoic acids, lower alkoxy celluloses, chitoseamine and polyalkylene oxide waxes, whereby both the fabric and the soil are imparted with a positive electrostatic charge and the soil is separated from the fabric by electrostatic repulsion and dispersed throughout the washing solution.
2. The method of cleansing a soiled synthetic textile fabric, which comprises washing said fabric at least once in a cation-active aqueous solution consisting essentially of water and from about 0.85 to about 1.5 gm./liter of a cation-active washing composition comprising (1) from about 23% to about 44% of an organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, (2) from about 33% to about 77% of a lower alkanoic acid and, (3) from about 0% to about 33% of an additive stable in said cationic active aqueous solution selected from the group consisting of aluminum salts of lower alkanoic acids, lower alkoxy celluloses, chitoseamine and polyalkylene oxide waxes, whereby both the fabric and the soil are imparted with a positive electrostatic charge and the soil is separated from the fabric by electrostatic repulsion and dispersed throughout the washing solution, and at least once in an anion-active aqueous solution capable of imparting a negative electrostatic charge to the fabric and the soil.
3. The method of cleansing a soiled synthetic textile fabric, which comprises washing said fabric in a cation-active aqueous solution consisting of water, from about 0.3 to about 0.5 gm./liter of a cation-active organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached

to the nitrogen atom an aliphatic radical containing a hydrocarbon chain having from 6 to 20 carbon atoms, and from about 0.5 to about 1.0 gm./liter of a lower alkanoic acid.

4. The method of cleansing a soiled synthetic textile fabric, which comprises washing said fabric in a cation-active aqueous solution consisting of water, from about 0.3 to about 0.5 gm./liter of a cation-active organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, from about 0.5 to about 1.0 gm./liter of a lower alkanoic acid, and about 0.5 gm./liter of an aluminum salt of a lower alkanoic acid.

5. The method of cleansing a soiled synthetic textile fabric, which comprises washing said fabric in a cation-active aqueous solution consisting of water, from about 0.3 to about 0.5 gm./liter of a cation-active organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, from about 0.5 to about 1.0 gm./liter of a lower alkanoic acid and from 0.01 to 0.5 gm./liter of an additive stable in said cationic active aqueous solution selected from the group consisting of aluminum salts of lower alkanoic acids, lower alkoxy celluloses, chitoseamine and polyalkylene oxide waxes.

6. A composition of matter for cleansing soiled synthetic textile fabrics consisting essentially of water and from about 0.85 to about 1.5 gm./liter of a cation-active washing composition comprising (1) from about 23% to about 44% of an organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, (2) from about 33% to about 77% of a lower alkanoic acid and, (3) from about 0% to about 33% of an additive stable in said cationic active aqueous solution selected from the group consisting of aluminum salts of lower alkanoic acids, lower alkoxy celluloses, chitoseamine and polyalkylene oxide waxes.

7. A composition of matter for cleansing soiled synthetic textile fabrics consisting essentially of water, from about 0.3 to about 0.5 gm./liter of a cation-active organic onium compound selected from the group consisting of aliphatic ammonium compounds having attached to the nitrogen atom an aliphatic radical containing a hydrocarbon chain having from 6 to 20 carbon atoms, at least

two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, and from about 0.5 to about 1.0 gm./liter of a lower alkanoic acid.

8. A composition of matter for cleansing soiled synthetic textile fabrics consisting essentially of water, from about 0.3 to about 0.5 gm./liter of a cation-active organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, from about 0.5 to about 1.0 gm./liter of a lower alkanoic acid, and about 0.5 gm./liter of an aluminum salt of a lower alkanoic acid.

9. A composition of matter for cleansing soiled synthetic textile fabrics consisting essentially of water, from about 0.3 to about 0.5 gm./liter of a cation-active organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl and cyclohexyl, pyridinium compounds having attached to the nitrogen atom an aliphatic radical containing a hydrocarbon chain having from 6 to 20 carbon atoms, from about 0.5 to about 1.0 gm./liter of a lower alkanoic acid, and from about 0.01 to 0.5 gm./liter of an additive stable in said cationic active aqueous solution selected from the group consisting of aluminum salts of lower alkanoic acids, lower alkoxy celluloses, chitoseamine and polyalkylene oxide waxes.

10. The method of cleansing a soiled polyamide fiber fabric, which comprises washing said fabric in a cation-active aqueous solution consisting essentially of water and from about 0.85 to about 1.5 gm./liter of a cation-active washing composition comprising (1) from about 23% to about 44% of an organic onium compound selected from the group consisting of aliphatic ammonium compounds having attached to the nitrogen atom an aliphatic radical containing a hydrocarbon chain having from 6 to 20 carbon atoms, at least two alkyl radicals having from 1 to 2 carbon atoms and a radical selected from the group consisting of ethyl, methyl, benzyl, and cyclohexyl, pyridinium compounds having attached to the nitrogen atom an aliphatic radical containing a hydrocarbon chain having from 6 to 20 carbon atoms and quinolinium compounds having attached to the nitrogen atom an aliphatic radical containing a hydrocarbon chain having from 6 to 20 carbon atoms, (2) from about 33% to about 77% of a lower alkanoic acid and, (3) from about 0% to about 33% of an additive stable in said cationic active aqueous solution selected from the group consisting of aluminum salts of lower alkanoic acids, lower alkoxy celluloses, chitoseamine and polyalkylene oxide waxes, whereby both the fabric and the soil are imparted with a positive electrostatic charge and

the soil is separated from the fabric by electrostatic repulsion and dispersed throughout the washing solution.
